United States Patent Office.

HENRY T. CARTER, OF PORTLAND, MAINE.

Letters Patent No. 79,104, dated June 23, 1868.

IMPROVEMENT IN CAR-TRUCKS FOR CHANGING GAUGE.

The Schedule referred to in these Letters Patent and making part of the same.

TO ALL WHOM IT MAY CONCERN:

Be it known that I, HENRY T. CARTER, of Portland, county of Cumberland, and State of Maine, have invented a new and useful Improved Mechanism for Changing Gauge of Car-Trucks; and I do hereby declare the following to be a full, clear, and exact description of the same, reference being had to the accompanying drawing, making a part of this specification, in which—

Figure 1 represents a plan of my car-truck.

Figure 2 represents a transverse sectional elevation of my truck, and table for adjusting same.

Similar letters indicate like parts.

The object of my invention is to produce a car-truck which is adjustable to any desired gauge of road, by means of an adjusting-platform, hereinafter described.

It consists of two frames, A A', figs. 1 and 2, between which are placed the car-wheels d, d', d'', and d''', fig. 1, d and d', fig. 2. These frames are each connected at the ends by means of "lugs," shown at b, b', b'', and b''', through which are passed strong iron bars or rods, m and m'. These rods are keyed at each end to the "lugs," and serve to strengthen and stiffen the truck-frame. The four wheels are secured to two telescopic axles, shown at x x', which may be keyed or not, as desired. In the frames are also the boxes and bearings of the wheels before mentioned, and it is intended to have "inside" and "outside" bearings to each wheel, so that my truck will rest upon eight bearings, instead of on four, as ordinarily constructed. The bolster B extends transversely over my truck-frames, in the usual manner, and is provided with a friction-plate, c, upon its lower surface, which is constructed with four shoulders, a, a', a'', and a''', fig. 2. This friction-plate rests upon two or more friction-rollers, shown at e and e', fig. 2, which have their bearings in the frames A A', and receive the entire weight of the car when running, and during adjustment. The upper or car-bolster is bolted to the car, and rests upon rubber springs, and the centre-pin and socket are constructed in the usual manner.

My table for adjusting car-trucks, shown in fig. 2, consists of two beams, C C', long enough to receive the entire car, or one truck of same, and are each provided with guard-rails, h and h', in addition to the usual rail o and o'. The beam C is stationary, and secured firmly to the foundation. The beam C' rests upon trucks or friction-rollers, f and f', and by this means is allowed lateral movement of sufficient distance to accomplish the desired change of gauge. This moving beam C' is provided with a set of screws, k, or gears l, or both, of sufficient power to "close" or "open" the table with a loaded car upon it.

Now, if a car provided with my trucks is gauged for the broad gauge of five feet six inches, and it be desired to change the gauge of the trucks, so that it may be run upon the narrow gauge of four feet eight and a half inches, it is moved down upon my table, (which is placed permanently at the station where the change of gauge occurs,) and the car or truck is stopped upon the table. The tread of the wheels will rest upon the ordinary rails o and o', while the guard-rails h and h' will come closely against the inside of the wheels. The pins or keys of the transverse rods 1, 2, 3, and 4, and of the axles, if any, are then removed, and the pressure, by means of proper gearing, applied to the beam C'. The frames and wheels of the truck will be gradually closed up toward each other, until the shoulders d' and d'' of the truck-bolster B press firmly against the frames. This will be the desired gauge of four feet eight and a half inches, and the pins or keys 1, 2, 3, and 4 being again inserted, the truck is run off on to the narrow-gauge road, which leads from one end of the adjusting-table. Should the truck be adjusted to the narrow gauge, and it be desired to change to the broader, the car is run on to the table again, the keys being removed as before, and the screw reversed. The car-trucks and wheels are extended until the shoulders d and d''' rest against the outside of the frames A A', as illustrated in the drawing. The keys being again inserted, the car is moved off upon the broad gauge, and is ready for the road.

I use this friction-plated bolster provided with the four shoulders, instead of the parallel motion, secured by Letters Patent granted me the 14th day of January, A. D. 1868. It will be perceived that this arrangement secures the bolster B in the centre of the truck at either gauge, the same as did the parallel motion before mentioned, and is much cheaper of construction.

The advantages of my invention are, that it provides a cheap and substantial car-truck, adapted to either gauge; and the table, being properly constructed and under cover, will be found to act much surer, especially in icy weather, than the converging rails generally resorted to in changing gauge.

I do not claim to be the first inventor of combined inside and outside bearings, nor do I claim to be the same of the telescopic axles; but

What I do claim, and desire to secure by Letters Patent, is—

1. The four shoulders, d , d' , d'' , and d''' , constructed on the bolster B, substantially as and for the purposes set forth.
2. The combination of the shoulders d , d' ; d'' , and d''' with the transverse rods, substantially as and for the purposes set forth.
3. The lateral-moving rail o' , with its guard-rail h' , in combination with the fixed rail and guard-rail o and h , substantially as and for the purposes set forth.
4. The combination of the lateral-moving rail o' and guard-rail h' , with their bed or beam, and friction-rollers or trucks, substantially as and for the purposes set forth.

HENRY T. CARTER.
